UNITED STATES PATENT OFFICE.

FRANCIS S. HIGGINS, OF PASADENA, CALIFORNIA.

FRAMING-SQUARE.

1,065,046.

Specification of Letters Patent. Patented June 17, 1913.

Application filed September 19, 1911. Serial No. 650,212.

To all whom it may concern:

Be it known that I, FRANCIS S. HIGGINS, a citizen of the United States, residing at Pasadena, in the county of Los Angeles and State of California, have invented certain new and useful Improvements in Framing-Squares, of which the following is a specification.

My invention relates to instruments for facilitating framing calculations.

It contemplates the provision of a framing instrument constructed in such manner and possessed of such characteristics that practically all of the problems that arise incidental to framing operations may be quickly and easily solved.

Other advantageous features of the invention will be fully understood from the following description and claims when the same are read in connection with the drawings, accompanying and forming part hereof, in which:

Figures 1 and 2 are plan views of the instrument showing the same set for different purposes hereinafter explicitly referred to. Fig. 3 is an enlarged fragmentary view showing the pivotally connected members of the instrument as relatively arranged and adjustably fixed with respect to each other to form a T-square. Fig. 4 is an enlarged perspective of one of the slidable members of the device. Fig. 5 is an enlarged detail view of one end portion of the intermediate member—*i. e.*, the member that extends between 35 and is designed to coöperate with the pivotally connected members. Fig. 6 is an enlarged perspective of the second slidable member. Fig. 7 is a detail section showing the manner in which the intermediate member is connected with the second-named slidable member.

Similar numerals of reference designate corresponding parts in all of the views of the drawings.

The pivotally connected members 1 and 2 are each graduated along one edge, as indicated by 3, the divisions being by preference in inches and twenty-fourths of inches. The pivotal connection is effected through a pintle 4 at the point of intersection of the graduated edges so as to permit of one member being moved relative to the other from the position where the graduated edges coincide to an angle of ninety degrees. It will also be noted here that the pivotally connected member 2 has an arcuate slot 5 which

receives a threaded post 6. This latter rises from the member 1 and receives a clamping nut 6^a that is adapted when fixed or set against the member 2 to adjustably fix the latter at the angle desired to the member 1.

One slidable member of the instrument is numbered 7, the other slidable member 8, and the intermediate member 9. In the preferred embodiment of my invention the member 7 comprises a body 10, channeled at 11 to receive the particular pivotally connected member 1 or 2 on which it is positioned, a transverse bar 12 fixed on the body and bridging the channel thereof, a threaded post 13 rising from said bridge bar, and a screw 14 bearing in one side wall of the referred to channel and designed to be set against the edge of one pivotally connected member to adjustably fix the member 7 thereto.

Like the slidable member 7 the slidable member 8 comprises a body 15, channeled at 16, and provided in one side wall of the channel with a set screw 16^a. Said member 8, however, differs from the member 7 in that it has alined recesses 17 in the side walls of its channel; also, in that its threaded post 18 rises from the bottom of one of the recesses 17. The threaded post 13 of the member 7 is equipped with a thumb nut 19, designed to be set against the intermediate member 9 at an intermediate point in the length thereof, and the threaded post 18 of the member 8 is provided with a similar nut 20, designed to be set against said intermediate member 9 at one end thereof, Figs. 1-3. Each of the slidable members 7 and 8 is provided, as shown, with graduations at opposite sides of its channel, this in order to assure the location of slide graduations adjacent the graduations on the pivotally connected members when the connected slidable members 7 and 8 and intermediate member 9 are reversed on the pivotally connected members 1 and 2 as will be understood by comparison of Figs. 1 and 2. The intermediate member 9 is slotted, at 30, to receive the threaded post 13 of slide member 7, is preferably graduated adjacent both of its edges as shown; the graduations being similar to those of the members 1 and 2, and is provided in one end with a notch 31 to receive the post 18, as best shown in Fig. 7.

The adaptability of the device to be used after the manner of an ordinary T-square is illustrated in Fig. 3, the slide members 7

and 8 and intermediate member 9 being in that case removed from the members 1 and 2, which are fixed by the nut 6^a in positions at right angles to each other. I would also 5 have it here understood that with the members 7, 8 and 9 removed, the members 1 and 2 may be so positioned relative to each other as to serve the purposes of an ordinary bevel. This latter, however, I have deemed 10 it unnecessary to illustrate.

In use of the device, for instance, in determining the length of rafters, the perpendicular blade 9 is adjusted upon the base member 1 to a number representing half 15 the width of the building. The member 2, which may be termed a hypotenuse blade, is then raised, so that the figure on the perpendicular blade representing the rise of the roof upon the hypotenuse blade will 20 indicate the length of the rafter. The angle between the members 2 and 9 gives the top cut and that between the members 1 and 2 gives the bottom cut of the rafter, while the angle at the pivot or members 1 and 2 is the 25 angle for the seat bevel at the lower end of the rafter. By different adjustments the device may be employed to give the rise of a roof, the side bevel of jack rafters, the 30 length of jack rafters, and the length, angles and bevels for hip rafters, etc.

It will be understood from the foregoing that when either of the slidable members of the instrument is grasped and moved, the intermediate member 9 will move the other 35 slidable member in the same general direction; and I would also have it understood that the slidable member 8 is beveled at 40, in order to enable it to run under the member 2 when it is moved inward to a position 40 adjacent the pivotal connection between the members 1 and 2.

In some instances when the slidable member 8 is arranged on the member 2, the slidable member 7 is dispensed with, and then 45 when the slidable member 8 is run in on the member 2 to a point adjacent the pivotal

connection, the kerf 41 in the end of member 8 serves to receive the member 1.

Having thus described the invention what is claimed as new, is:—

1. An instrument of the character described, comprising graduated members pivotally connected together, means for adjustably fixing said members with respect to each other, channeled slidable members arranged on the pivotally connected members and graduated correspondingly thereto; one of said slidable members having a recess disposed at a right angle to its length, an intermediate member disposed in said recess and 55 fixed to said slidable member and extending across the other slidable member; said intermediate member being graduated correspondingly to the other members and being provided with a longitudinal slot, a post on 60 such other slidable member disposed in said slot of the intermediate member, and means on said post for adjustably fixing the intermediate member to such other slidable member. 65

2. An instrument of the character described comprising graduated members pivotally connected together, means for adjustably fixing said members with respect to each other, channeled slidable members arranged on the pivotally connected members and graduated correspondingly thereto, one of said slidable members having a recess disposed at right angles to its length, an intermediate member disposed in said recess 70 and fixed to said slidable member and extending across the other slidable member, said intermediate member being graduated correspondingly to the other members, and means for connecting said intermediate 75 member to the other slidable member. 80

In testimony whereof I affix my signature in presence of two witnesses.

FRANCIS S. HIGGINS.
